his Attorney

UNITED STATES PATENT OFFICE.

JACOB HAISH, OF DE KALB, ILLINOIS.

DOOR FOR RAILWAY-CARS.

SPECIFICATION forming part of Letters Patent No. 398,147, dated February 19, 1889.

Application filed February 23, 1888. Serial No. 265,028. (No model.)

To all whom it may concern:

Be it known that I, JACOB HAISH, a citizen of the United States, residing at De Kalb, in the county of De Kalb and State of Illinois, have invented certain new and useful Improvements in Vestibule-Doors for Railway-Coaches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention has reference to improvements in vestibule-doors for railway-coaches; and it pertains especially to certain novel mechanism whereby the side opening between the coaches and the open space occupied by the platform can be opened and closed coincidentally.

As my invention is located at and applied to the end of the coach, I do not deem it necessary to show or describe any other portion of the latter than will render intelligible the construction and operation of my invention.

In the drawings, Figure 1 is a side view of one end of a railway-coach provided with my invention. In this figure the side of the door which closes the space at the side of the platform is shown thrown back alongside of the end of the car, the adjacent end of the latter being indicated in dotted lines in said figure. The lid or trap-door, which, when the sliding door is thrown out, closes the space over the platform-steps, is shown in said figure in a vertical position, so as to open the passage over the platform-steps. In this figure the closed position of the door is also shown in dotted lines. Fig. 2 is a partial end view of a railway-coach provided with my invention. Fig. 3 is a detail in section showing how the door-latch can be operated from the inside of the car.

A is the usual railway-coach provided with the platform B at each end, but one of which is shown.

C are the usual side steps leading to and from the platform B and means of access to the latter.

B' is the outer extremity of the platform

B, from which rises the usual standard or vertical guard, D.

E is a sliding or folding door suitably supported upon the track E' and rollers F at the side of and parallel with the coach A, thus adapted to be carried to and from the steps at the side of the platform B, and when not used for closing said interval be slid back alongside of the exterior of the car. When in the latter position, the door E is held from lateral jar or shaking by the projection of these outer edges into two or more obliquely-seated cleats, I, attached to the sides of the coach A in such position as to receive and clamp the door E against the side of said coach.

The door E extends vertically from a short distance below the plane of the platform B and slightly above the lower plane of the projecting roof A' of the car A, and will of itself close the openings at the side of said platform, it being understood that the similar door, E, is not locked when attached to the opposite side of said platform.

As is well known, the insertion of the steps C in the side of the platform B necessitates the cutting back or withdrawal of the latter within the outer line of the coach A, so that, notwithstanding the external closing of the side of the platform B by means of the door E, there remains an open space at the sides of the platform B, occupied in part by the steps C, and as the object in providing the door E is to effectually close the sides of the platform B against the admission of storm, smoke, or dust, such effect would not be fully accomplished without some means of closing the lower space aforesaid at the sides of the platform. To effect this, a lid or trap-door, D, is hinged to the coach A at or near the lower adjacent corner of the latter and within the door E in such relation to the space aforesaid at the side of the platform B as to be susceptible of being thrown over and effectually closing said space, the lid D when in a horizontal position being in fact a lateral extension of the platform B outwardly to the external line of the coach A. To the end that the raising and lowering of the lid D may be coincident with the shifting of the door E, a pitman, G, is provided, the inner end of which

is pivotally seated at its inner end on the inside of the door E, and in the outer end of which is pivotally attached, near the top or free end, the lid D. The relation and size of the respective parts is such that when the door E is shifted inward a distance equal to its own width the pitman G will raise the lid D from a horizontal to a vertical position, and thus the space at the side of the platform B is opened laterally by the withdrawal of the door E, and the space occupied by the steps C is opened by raising of the lid D at the same time, in which position of the parts access to and from the platform B is unobstructed. When the door E is shifted to the limit of its outthrust, the pitman G in the same movement will throw the lid D in a horizontal position and there hold the same, thus effectually closing the space from the steps C. The lid D, therefore, and the door E jointly close the bottom and sides of the space at the platform B, as aforesaid, at the extremity of the car, and a like device, as before described, being provided upon the adjacent end of the adjoining car, the outward throw of the door E will effectually close the space between the coaches both upon the sides and bottom, and thus exclude storm, dust, smoke, and other matters from the space between the ends of the coach and render the passage from one coach to the other comfortable, convenient, and safe. By connecting the pitman to the door near its top the leverage in securing the motion of the lid is very small, and but very little more force will be required to move both door and lid than would be required to actuate the door alone.

H is a suitable latch pivoted at its inner end, at H', to the inner side of the door E, and provided at its outer or free end with the downwardly-projecting lug 2, adapted to engage the top of the ordinary rail, 3, at the outer extremity of the platform B, and thus hold the door E from casual withdrawal when at the limit of its outthrust.

If desired, the latch or lever H can be extended from beyond its pivotal seat H' into and within the coach A, so as to be accessible and operative from within said coach. The pivotal seat H' of the latch H is extended to the outside of the door E and there provided with the knob K, by means of which the latch H can be disengaged from the outside of the door E. The latch H is disengaged from the inside of the door E by merely raising said latch from any point between its pivotal seat and engaging end or by the projected ends suggested, as aforesaid, within the coach A.

When the door is slid back and the lid raised up, the operative parts—to wit, the pitman G and latch H—are withdrawn, so as to be between the sliding door and the side of the car, and thus entirely out of sight. The head of the latch will come directly at the side of the lid and not at all exposed to do any harm to the clothes of the passengers entering or leaving the car.

The advantage of simultaneously closing or opening the door and lid, and of automatically locking the door and lid when closed, and of closing the space at the end of the railway-coach occupied by the platform thereof, is perhaps sufficiently obvious. By this means, in the easiest and simplest way, the parts are operated, and when the door and lid are shut (that is, when the door is drawn out and the lid down) and the latch caught upon the car-rail a secure closure is obtained, and the passage from one coach to another may be convenient and safe, and the smoke and dust which usually draw into the car when the end doors are open are excluded, and therefore in warm weather it is feasible to have all of the doors open, so as to afford a draft of air and ventilation from one end of the train to the other. The danger of falling from the platform when the cars are in motion is also hereby avoided.

What I claim as my invention, and desire to secure by Letters Patent of the United States, is—

1. In a railway-coach, the combination of the door E, adapted to slide in line therewith, the lid D, hinged on the platform of said coach perpendicular to said door, the pitman G, connecting the top of lid D with the side of door E, and the latch H, projected within said coach, whereby said door E can be operated from within said coach and said lid raised and lowered coincidently with the sliding of said door, substantially as described.

2. In a railway-coach, the combination of a door, E, suitably supported at the side and near the end of said coach, and adapted to be slid back and forth, a lid, D, hinged to said coach at or near the lower outer corner thereof, and pitman G, connecting said door and lid, whereby the shifting of the door E to and from the side of the end platform of said coach will coincidently raise and lower the lid D, so as to open and close the step-space at the side of said platform, the pitman being drawn between the car side and door when the door is slid back, substantially as shown, and for the purpose described.

3. In a railway-coach having a rail, 3, in front of the platform, a door adapted to be slid to and fro at the side, combined with a latch pivoted at its inner end to the inner side of the door and adapted to be wholly withdrawn between the car side and door when the door is open, and having a knob on its pivot, whereby it can be lifted either from the outside or inside of the coach.

4. The combination, in a railway-coach, of a sliding door at the end, a hinged lid to cover the car-steps, and a pitman pivoted at one end to the door and at the other near the top of the hinged lid, whereby the door and lid can be simultaneously operated, for the purposes set forth, and when the door is open the pitman is concealed from view, substantially as set forth.

5. In a railway-coach, a sliding door and a hinged lid for covering the car-steps, and connections between the lid and door, whereby simultaneously the door and lid can be operated, substantially as described.

6. In a railway-coach, a sliding door and a hinged lid to cover the car-steps, and means, substantially as described, for connecting the two, so that they can be operated simultane-

ously, and a lock or latch for securely holding the door closed and the lid down, all substantially as described.

In testimony whereof I affix my signature in presence of two witnesses.

JACOB HAISH.
